UNITED STATES PATENT OFFICE.

WILLIAM J. REILLY, OF DENVER, COLORADO, ASSIGNOR TO THE BABCOCK & WILCOX COMPANY, OF BAYONNE, NEW JERSEY, A CORPORATION OF NEW JERSEY.

STEAM-BOILER FURNACE.

1,305,409.

Specification of Letters Patent. Patented June 3, 1919.

Application filed October 10, 1916. Serial No. 124,760.

To all whom it may concern:

Be it known that I, WILLIAM J. REILLY, a citizen of the United States, residing at Denver, in the county of Denver, State of Colorado, have invented certain new and useful Improvements in Steam-Boiler Furnaces, of which the following is a specification.

My invention relates to steam boiler furnaces and more particularly to the provision of an ash flume for the removal of ashes falling from the rear of a chain grate stoker and will be understood by reference to the accompanying drawings, in which Figure 1 is a vertical longitudinal section, more or less diagrammatic, of a portion of a water tube boiler, stoker and ash pit; Fig. 2 a vertical section of a modified arrangement of the flume; Fig. 3, a vertical transverse section to the ash pits of a battery of boilers illustrating the use of a common flume; Fig. 4, an enlarged view of one of the dampers of Fig. 3, showing the damper closed; and Fig. 5, a vertical longitudinal section of the rear of the furnace chamber of the boilers of Fig. 3.

Similar reference numerals indicate similar parts in the several views.

In Fig. 1, I have shown an arrangement for a single boiler in which the numeral 1 designates a portion of the tubes of a bank of horizontally inclined water tubes, which will be supported in the usual way above the furnace chamber. The boiler is fired by a chain grate stoker 2, the frame of which is mounted on wheels adapted to travel upon tracks 3 to enable the stoker to be run into and out of the furnace chamber. At the rear of the furnace chamber is a bridge wall 4 extending upwardly from the floor to the transverse baffle 5. The bridge wall is protected by a water box 6 which may be connected to the boiler circulation through pipes 7.

Below the stoker is a pit 8, the floor of which, at its inner end, is so constructed as to form a flume 9, which, as shown in Fig. 1, is immediately below the rear end of the stoker. Hinged to a bracket 10 is a gate or damper 11, which in its open position is at the right, alongside the front of the downward extension of the bridge wall 4, so that the ash and fuel refuse falling over the rear end of the stoker may fall unobstructed into the flume 9. To effect the removal of the ash and fuel refuse from the flume, provision

will be made to flush the flume with water either continuously or intermittently. The damper 11 is of such length that when moved to the left, or closed, it will reach the left-hand wall of the flume 9. For the purpose of swinging or moving the damper 11, I provide a chain 12 secured thereto and extending toward the front of the pit 8 so as to be accessible to the operator. When the damper 11 is swung to open position it acts to dump or aid in dumping the ash and fuel refuse lying partly thereon, into the flume 9.

Hinged to the stoker frame is a second gate or damper 13 of such length as to reach the floor of the pit 8. The damper 13 is shown in its normal position in Fig. 1 and extends from the stoker frame to substantially the floor of the pit 8, its purpose being to prevent an undue amount of air entering the furnace at the rear of the stoker. The damper 13 may be raised by means of a chain 14, extending to the front of the stoker, when it is desired to gain access to the flume 9 to inspect it, or for any other purpose.

Placed at the floor line and in front of the bridge wall 4, is a cleaning door 17 having its sill sloping inwardly. The purpose of this door is to afford a means of observation of the operation of the flume and of the ash accumulation, and to permit of the mechanical cleaning of the flume from the outside of the boiler setting should the flow of water become obstructed by an undue accumulation of ash.

In Fig. 2 a modification is shown in which the flume 9' is built in the floor of the pit 8 a sufficient distance from the front of the bridge wall 4 to provide a floor 15 between the bridge wall and the flume to receive the ash and fuel refuse falling from the rear of the stoker. Located substantially at the junction of the ash pit floor and the face of the bridge wall is a perforated pipe 16, through which water is discharged to wash the ash and fuel refuse from the floor 15, into the flume 9'. This pipe may be controlled by a suitable valve.

In Figs. 3, 4 and 5, I have shown an arrangement applicable to a battery of boilers having a common flume 18, into which the ash and fuel refuse are discharged, the floor of the flume being given a slight downward inclination in the direction of the flow of the water. The latter is admitted through a

valved pipe 19 either continuously or intermittently. In this arrangement, the dampers 11 are closed by moving them to the left, as shown in full lines in Fig. 5, when one of the boilers of the battery is shut down to thereby prevent cold air rushing in at the rear and flowing to the other boilers, or to minimize as much as possible the air leakage which may occur between boilers working on the same flume and on the same smoke stack. In Fig. 3, the second damper 11 from the left is shown as open, or in its right-hand position. The dampers 11 of the other boilers are shown as closed or in their left-hand position over the flume.

What I claim and desire to secure by Letters Patent of the United States is:—

1. The combination with a boiler of a chamber extending underneath the same to a point intermediate its length, a mechanical stoker located in said chamber, the inner portion of the chamber having a transversely extending flume below the rear portion of

the stoker, means for flowing water through the flume, a damper supported above the flume and adapted to be moved over the same, and an air damper between the inner portion of the chamber and the flume.

2. The combination with a plurality of boilers each having a chamber extending beneath and terminating intermediate the length of the boiler, mechanical stokers in said chambers, a flume common to all the chambers and extending along the inner floor portions thereof, dampers arranged above the flume and adapted to be moved to cut off each chamber from its portion of the common flume, and means for flowing water through said flume.

In testimony whereof I have hereunto signed my name in the presence of two subscribing witnesses,

WILLIAM J. REILLY.
